UNITED STATES PATENT OFFICE

JAMES J. VANHORN, OF WILKINSBURG, AND HARRY C. VANTASSEL, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA

RAILWAY INTERLOCKING APPARATUS

Application filed October 15, 1929. Serial No. 399,762.

Our invention relates to interlocking apparatus for the control of railway switches and signals, and has for an object the provision of novel and improved means for the 5 release of detector locking in the event of failure of the track circuits which control such locking.

We will describe three forms of interlocking apparatus embodying our invention, and 10 will then point out the novel features thereof in claims.

In the accompanying drawings, Fig. 1 is a diagrammatic view showing one form of apparatus embodying our invention, adapted 15 for use in connection with alternating current track circuits. Fig. 2 is a diagrammatic view showing a modification of a portion of the apparatus shown in Fig. 1, but adapted for use with track circuits of any character. 20 Fig. 3 is a diagrammatic view showing another modification of a portion of the apparatus shown in Fig. 1 and embodying our invention, and including an auxiliary interlocking machine lever for the release of the 25 electric locking.

Similar reference characters refer to similar parts in each of the views.

Referring first to Fig. 1, the reference characters T^1 and T^2 designate two parallel 30 railway tracks. Track T^1 is divided by insulated joints 2 to form two track sections A^1 and A^2 , while track T^2 is similarly divided to form a track section A^3 . The two tracks are connected by a crossover comprising 35 a switch H^2 located in section A^2 and a switch H^2_a located in section A^3 . The two tracks are connected by a second crossover comprising a switch H^1 located in section A^1 , and a switch H^1_a located in section A^3 .

40 Section A^1 is provided with a track circuit comprising a track relay R^1 and a transformer D^1 , the secondary of which is connected with the rails of the section. The primary of transformer D^1 is connected with 45 a source of alternating current which is not shown in the drawing, but the terminals of which are designated by the reference characters X and O . Section A^2 is provided with a similar track circuit, comprising a transformer D^2 and a track relay R^2 , while sec-

tion A^3 is provided with a similar track circuit comprising a transformer D^3 and a track relay R^3 .

A power-off relay P is connected with the terminals X and O of the source of track 55 circuit current, so that this relay is normally energized, but becomes de-energized in the event of failure of the source of current.

Traffic over the sections A^1 , A^2 and A^3 is 60 controlled by signals S^1 , S^2 , S^3 and S^4 , which signals are controlled by suitable apparatus forming no part of our present invention, except that the circuits for these signals include a contact 13 of a slow-acting device E , 65 as hereinafter explained.

The switches H^1 and H^1_a are controlled by a manually operable lever V^1 , whereas, the switches H^2 and H^2_a are controlled by a second manually operable lever V^2 . These levers will usually be included in an interlocking machine, and may control the switches in any suitable manner. The control of the switches by the levers forms no part of our 70 present invention, and, consequently, the controlling apparatus is omitted from the drawing. Each lever has a normal position n , a reverse position r , a normal indication position f , and a reverse indicating position t . Lever V^1 is provided with an electric lock 75 comprising a magnet L^1_N , which controls a dog 20 co-acting with a segment 14 to lock the lever in its normal position except when the magnet is energized. The lever is provided with a second electric lock comprising 80 a magnet L^1_R , controlling a dog 20 which contacts with a segment 15 to lock the lever in the reverse position except when the magnet is energized. Lever V^2 is provided with similar 85 electric locks L^2_N and L^2_R .

The manually operable slow-acting device E comprises a normally closed contact 13 and a normally open contact 12, which contacts are so arranged that contact 13 opens immediately upon the beginning of the operation of the device, whereas, contact 12 does not close until the expiration of a given time interval after the operation of the device has begun.

As shown in the drawing, all parts of the 100

apparatus are in their normal positions. Lock magnet L^1_N of lever V^1 is energized by virtue of a circuit which passes from terminal B of a suitable source of current, through front contact 3 of the power-off relay P, front contact 5 of track relay R^3 , front contact 6 of track relay R^1 , contact nf of lever V^1 , and magnet L^1_N to terminal C of the same source of current. Lock magnet L^2_N of lever V^2 is likewise energized by virtue of a circuit which passes from terminal B, through front contact 3 of relay P, front contact 5 of relay R^3 , front contact 7 of relay R^2 , contact nf of lever V^2 , and lock magnet L^2_N to terminal C. It follows that both levers V^1 and V^2 are unlocked, so that either lever may be reversed to reverse the switches which it controls. If, however, track section A^1 is occupied by a train, track relay R^1 will be de-energized, so that the circuit for lock magnet L^1_N will be open and lever V^1 can not be reversed. If track section A^2 is occupied, track relay R^2 will be de-energized, so that lock magnet L^2_N will be de-energized and lever V^2 can not be reversed. If track section A^3 is occupied, track relay R^3 will be de-energized, so that both of the normal lock magnets will be de-energized and neither lever can be released.

Assuming that lever V^1 has been reversed, to reverse the switches which it controls, then if track relays R^1 and R^3 are both energized, the reverse lock magnet L^1_R will be energized by a circuit which passes over the front contacts of these two relays and contact tr of lever V^1 . It follows that if both of these track relays are energized, lever V^1 may be restored to its normal position, but that if either of these track relays is de-energized, the lever will be locked in its reverse position. Similarly, if lever V^2 is reversed and track relays R^2 and R^3 are both energized, the lever may be restored to its normal position, but if either of these track relays is de-energized, the lever will be locked in its reverse position.

In the event of failure of the source of alternating track circuit current, the power-off relay P will be de-energized, so that all of the lock magnet circuits will be opened at front contact 3 of this relay. The locking may then be released by reversing the manually operable slow-acting device E. When contact 12 of this device closes, an auxiliary circuit will be closed for lock magnet L^1_N , which circuit passes from terminal B, through back contact 3 of relay P, contact 12 of slow-acting device E, back contact 6 of track relay R^1 , contact nf of lever V^1 , and the lock magnet L^1_N to terminal C. If lever V^1 is in the reverse position when this occurs, reverse magnet L^1_R will be energized instead of the normal magnet L^1_N . Assuming that lever V^2 is in the normal position, an auxiliary circuit for magnet L^2_N will be closed, which circuit passes from terminal B, through back contact 3 of relay P, contact 12

of device E, back contact 7 of track relay R^2 , contact nf of lever V^2 , and magnet L^2_N to terminal C. If lever V^2 is in the reverse position when a power failure occurs, magnet L^2_R instead of magnet L^2_N will be energized.

The circuits for signals S are all controlled by the normally closed contact 13 of the slow-acting device E, so that immediately upon the beginning of the operation of this device, these signals are all placed in the stop position and no one of them can be cleared until the device E is restored to its normal position.

It will be seen from the foregoing, that in the event of a failure of the source of track circuit current, the switch controlling levers may be released to operate the switches after the time interval required for the operation of the slow-acting device E.

Lever V^1 may be provided with an indication lamp L^1 which is connected in multiple with the lock magnets for this lever, so that when the lamp is lighted the operator is informed that track relays R^1 and R^3 and power-off relay P are all energized. Lever V^2 may be provided with a similar lamp L^2 . The circuit for each of these lamps is completed through a front contact 4 of the power-off relay P, so that neither lamp can be lighted when this relay is deenergized even though the slow acting device E may have been operated to close contact 12. The complete circuit for lamp L^1 is from terminal B through front point of contact 3 of relay P, contact 5 of relay R^3 , front point of contact 6 of relay R^1 , lamp L^1 , and front contact 4 of relay P to terminal O. The circuit for lamp L^2 will be understood without being traced in detail.

Referring now to Fig. 2, the apparatus is the same as that shown in Fig. 1, except that the power-off relay is omitted, the apparatus in Fig. 2 being suitable for use with direct current track circuits which usually have an individual source of current for each section. The circuits for the lock magnets are the same as in Fig. 1, except that these circuits omit the power-off relay contact. In the event of failure of the track circuit for section A^3 , track relay R^3 will be de-energized, whereupon, the lever lock magnets may be released by the operation of the slow-acting device E, the circuits for these magnets then including back contact 5 of relay R^3 . Similarly, in the event of failure of the track circuit for section A^1 , relay R^1 will be de-energized, and the lock magnets may then be released by a circuit including contact 12 of device E and back contact 6 of relay R^1 . In the event of failure of the track circuit for section A^2 , track relay R^2 will be de-energized and the lock magnets for lever V^2 may then be released by a circuit including a back contact 7 of relay R^2 .

Referring now to Fig. 3, the apparatus is the same as that shown in Fig. 1, except that

the power-off relay P is omitted and the auxiliary circuits for the lock magnets are controlled by an auxiliary lever V³ incorporated in the same interlocking machine as the levers V¹ and V². Lever V³ is locked in the normal position by the co-action of a segment 16 with a slow-acting manually operable device E¹, and can be reversed only upon the expiration of a fixed interval of time after the operation of the device E¹ has begun. Immediately upon the beginning of the operation of the device E¹, contact 17 opens, thereby opening the circuits for all the signals governing traffic over the switches controlled by levers V¹ and V². The normal circuits for the lock magnets of these levers are the same as in Fig. 2. In the event of failure of the track circuit for section A³, track relay R³ will be de-energized, and after the operation of slow-acting device E¹ has been completed lever V³ may be reversed to close an auxiliary circuit for the lock magnets of lever V¹, which circuit includes reverse contact 18 of lever V³, back contact 5 of track relay R³ and front contact 6 of relay R¹. The remaining auxiliary circuits for the lock magnets of levers V¹ and V² will be apparent from the drawing and need not be traced in detail.

Although we have herein shown and described only three forms of apparatus embodying our invention, it is understood that various changes and modifications may be made therein within the scope of the appended claims without departing from the spirit and scope of our invention.

Having thus described our invention, what we claim is:

1. In combination, a section of railway track provided with a switch, a track circuit including a track relay for said section, a manually operable lever for the control of said switch, an electric lock for said lever, a main circuit for said lock including a front contact of said relay, a manually operable slow-acting device, and an auxiliary circuit for said lock including a back contact of said track relay and a normally open contact controlled by said slow-acting device.

2. In combination, a section of railway track provided with a switch, a track circuit including a track relay for said section, a manually operable lever for the control of said switch, an electric lock for said lever, a main circuit for said lock including a front contact of said relay, a manually operable slow-acting device, a signal governing traffic over said switch, a circuit for said signal including a normally closed contact controlled by said slow-acting device, and an auxiliary circuit for said lock including a back contact of said track relay and a normally open contact controlled by said slow-acting device.

3. In combination, a section of railway track provided with a switch, a track circuit for said section including a source of alter-

nating current and a track relay, a power-off relay connected with said alternating current source, a manually operable lever for the control of said switch, an electric lock for said lever, a main circuit for said lock including a front contact of said power-off relay and a front contact of said track relay, a manually operable slow-acting device, and an auxiliary circuit for said lock including a back contact of said power-off relay and a back contact of said track relay as well as a normally open contact controlled by said slow-acting device.

4. In combination, a section of railway track provided with a switch, a track circuit including a track relay for said section, a manually operable lever for the control of said switch, an electric lock for said lever, a main circuit for said lock including a front contact of said track relay, an auxiliary lever having a normally open contact, a slow-acting device for releasing said auxiliary lever, and an auxiliary circuit for said lock including a back contact of said track relay and the normally open contact of said auxiliary lever.

5. In combination, a section of railway track provided with a switch, a track circuit for said section including a source of alternating current and track relay, a power-off relay connected with said alternating current source, a manually operable lever for the control of said switch, an electric lock for said lever, a main circuit for said lock including a front contact of said power-off relay and a front contact of said track relay, a manually operable slow-acting device, a signal governing traffic over said switch, a circuit for said signal including a normally closed contact controlled by said slow-acting device, and an auxiliary circuit for said lock including a back contact of said power-off relay and a back contact of said track relay as well as a normally open contact controlled by said slow-acting device.

6. In combination, two sections A¹ and A² of railway track, track circuits including track relays R¹ and R², respectively for said sections, switches H¹ and H² in said two sections respectively, manually operable levers V¹ and V² for the control of said switches H¹ and H² respectively, an electric lock for each lever, a main circuit for the lock for lever V¹ including a front contact of relay R¹, a main circuit for the lock for lever V² including a front contact of relay R², a manually operable slow-acting device, an auxiliary circuit for the lock for lever V¹ including a back contact of relay R¹ and a normally open contact controlled by said device, and an auxiliary circuit for the lock for lever V² including a back contact of relay R² and said normally open contact.

7. In combination, two sections A¹ and A² of railway track, track circuits including

track relays R^1 and R^2 respectively for said sections, switches H^1 and H^2 in said two sections respectively, manually operable levers V^1 and V^2 for the control of said switches H^1 and H^2 respectively, an electric lock for each lever, a main circuit for the lock for lever V^1 including a front contact of relay R^1 , a main circuit for the lock for lever V^2 including a front contact of relay R^2 , a manually operable slow-acting device, signals governing traffic over said switches, circuits for said signals including a normally closed contact controlled by said slow-acting device, an auxiliary circuit for the lock for lever V^1 including a back contact of relay R^1 and a normally open contact controlled by said device, and an auxiliary circuit for the lock for lever V^2 including a back contact of relay R^2 and said normally open contact.

20 In testimony whereof we affix our signatures.

JAMES J. VANHORN.
HARRY C. VANTASSEL.
